UNITED STATES PATENT OFFICE

2,530,340

HUMIDOR

Solomon M. Sager, Chicago, Ill.

Application July 8, 1946, Serial No. 682,094

1 Claim. (Cl. 299—24)

1

This invention relates to a humidor and more particularly to a humidor containing variegated moisture-liberating material, the appearance of which affords a visual indication as to the moistened condition of the material.

In accordance with my present invention, I provide a tubular container including a transparent envelope or window, through which the colored moisture-liberating material is visible. The wall of the envelope, or window, is perforated to permit liberation of moisture into the space to be humidified, such as the interior of a tobacco pouch, or the like. In order to moisten the moisture-liberating material, it is merely necessary to immerse the humidor in water and allow it to stand until the color change of the material indicates that it has been saturated with moisture. The moisture is then given off through the openings in the envelope or window to maintain the surrounding air in a relatively humid condition.

It is, therefore, an important object of this invention to provide a humidor containing material adapted to give off moisture as required and to provide a colored material that indicates when the material is in a moist or a dry condition.

It is a further important object of this invention to provide a humidor of improved and novel construction that can be used in tobacco pouches and the like and that will give off moisture vapor to maintain the desired relative humidity without, however, allowing liquid water to escape into the contents of the pouch, or the like.

Other and further important objects of this invention will be apparent from the disclosures in the specification and the accompanying drawings.

On the drawings:

Figure 1 is a plan view of a tobacco pouch, showing a wall thereof broken away to indicate the positioning therein of a humidor embodying the principles of my invention.

Figure 2 is an enlarged longitudinal sectional view of the humidor, with parts in elevation.

Figure 3 is a further enlarged sectional view taken substantially along the line III—III of Figure 2.

The reference numeral 10 indicates a tobacco pouch of any conventional type for containing tobacco, indicated at 11. A humidor, indicated by the reference numeral 12, is illustrated in its position within the pouch 10 surrounded by the tobacco 11.

The humidor 12 comprises an outer casing 12a which may be made up of a metal cylinder closed

2

at its ends by means of disks 13 and 13a. Said enclosure disks 13 and 13a may be press-fitted or otherwise secured in the open ends of the tubular body portion 12a.

Before closing the ends of the casing 12a, an open-ended cylindrical tube 14, preferably of transparent plastic material, is loosely fitted within the casing 12a and the casing then closed by the disks 13 and 13a. Said tube 14 is filled with moisture-liberating material, preferably in granular form, such as the material 15, and the wall of said tube is provided with a plurality of small openings 16, some of which at least register with a larger, elongated opening 17 formed in the casing 12a.

The material 15 is preferably a clay, such as fuller's earth, having a capacity for absorbing a proportionately large volume of water and of liberating said water as moisture vapor under conditions of relatively low humidity. The material 15 is also preferably colored so that its dry or moisture-saturated condition can be readily ascertained by visual inspection.

Where fuller's earth is used as the moisture-liberating material, a fuller's earth of around 16 to 30 mesh, free of loose dust particles, is preferred. The granules of fuller's earth may be dyed in any suitable manner, as by agitating the fuller's earth in a bath of the dye dissolved in water or alcohol. Fuller's earth has the property of adsorbing the dye from its solution. After the fuller's earth has been thoroughly mixed with the dye solution, the earth is washed and screened over a 40-mesh screen. It is then either air or oven dried, but should not be dried too fast or heated too hot so as to destroy the dye.

In addition to the dye, a wetting agent may be added to the fuller's earth, or other moisture-liberating material, to assist in wetting the earth and saturating it more quickly with water. A wetting agent such as a sulfated or sulfonated high molecular weight alcohol, as for instance "Duponol," or the like, is satisfactory. Amounts of around 1% of wetting agent by weight of the earth, or less, has been found sufficient.

Before using the humidor, it is immersed in water to allow the granular material 15 to become saturated. The water seeps into the interior 50 of the tube 14 through the openings 16 and also through the loose joints provided around the ends of the tube 14 and the corresponding ends of the casing 12a. The color of the granular material 15 darkens considerably as water is absorbed, thereby indicating when uniform satu-

ration of the granular material with water has been reached.

In use, water vapor is given off through the openings 16, as well as through the narrow clearance spaces, as indicated by the reference numeral 18 (Figure 3) to pass out through the elongated opening 17 in the outer casing 11. The size and number of the openings 16 and the extent of the clearance space 18 are so regulated as to permit the liberation of moisture vapor at the desired rate. Since the granular material 15 strongly binds the liquid water to itself, there is no danger of liquid water exuding through the openings 16 to wet the surrounding material, such as the tobacco, unduly.

When the color of the granular material 15 indicates that it is again dry, it can be remoistened as described above and replaced in the tobacco pouch or other receptacle.

While the drawings and the description illustrate and describe a cylindrical shaped humidor, it is to be understood that the tubular form may be of any selected cross-sectional shape such as rectangular, triangular or hexagonal. Any other apertured shape of outer casing may be selected to suit requirements for enclosing a correspondingly shaped transparent and apertured inner material carrying envelope or container.

It will, of course, be understood that various details of construction may be varied through a wide range without departing from the principles

of this invention, and it is, therefore, not the purpose to limit the patent granted hereon otherwise than necessitated by the scope of the appended claim.

I claim as my invention:

A humidor comprising a cylindrical shell having an elongated opening and closed ends, an open-ended transparent tube fitted in said shell and having moisture-liberating openings coinciding with said elongated opening and moisture-liberating material contained within said shell, said moisture-liberating material consisting essentially of granular clay capable of liberating absorbed moisture, a wetting agent and a dye capable of undergoing a color change as the moisture content of the clay decreases.

SOLOMON M. SAGER.
